UNITED STATES PATENT OFFICE

96,260

DESIGN FOR A HAND MIRROR

Belle Kogan, New York, N. Y., assignor to Celluloid Corporation, a corporation of New Jersey

Application May 24, 1935, Serial No. 56,991

Term of patent 7 years

To all whom it may concern:

Be it known that I, Belle Kogan, a citizen of the United States, residing at New York, county and State of New York, have invented a new, original, and ornamental Design for Hand Mirrors, of which the following is a specification, reference being had to the accompanying drawing, forming a part thereof.

In the accompanying drawing:

Fig. 1 is a front view of a hand mirror showing my new design; and

Fig. 2 is a side view of the mirror shown in Fig. 1; and

Fig. 3 is a view of the back of the mirror shown in Fig. 1.

As shown in the drawing the mirror is beveled and oval shaped and the curved handle is joined to the rear side of the mirror frame at its central portion.

I claim:

The ornamental design for a hand mirror or similar article, substantially as shown and described.

In testimony whereof, I have hereunto subscribed my name.

BELLE KOGAN.
